ABSTRACT OF THE DISCLOSURE

This invention relates to N,N-disubstituted α -sulfuryl anhydride acetamides which are useful as fire retardants, rust inhibitors and intermediates for petroleum additives and agricultural chemicals.

This invention relates to sulfur containing acetamides. The sulfur containing acetamides of this invention are represented by the formula

wherein R and R¹ are each selected from the group consisting of hydrogen, alkyl of not more than 12 carbon atoms and haloalkyl of not more than 12 carbon atoms containing 1, 2 or 3 halogen atoms, R² and R³ are each selected from the group consisting of alkyl of not more than 12 carbon atoms, alkenyl of not more than 12 carbon atoms and phenyl, X and X¹ are halogen (Cl, Br, F and I), and α and β are each integers from 0 to 5 inclusive.

In the above formula R and R¹ can be hydrogen, alkyl such as methyl, ethyl, n-propyl, isopropyl, n-butyl, sec-butyl, isobutyl, tert-butyl, amyl, hexyl, heptyl, octyl, nonyl, decyl, dodecyl and the various homologues and isomers of alkyl having from 1 to 12 carbon atoms and haloalkyl such as chloromethyl, iodomethyl, bromomethyl, fluoromethyl, chloroethyl, iodoethyl, bromoethyl, fluoroethyl, trichloromethyl, triiodomethyl, tribromomethyl, trifluoromethyl, dichloroethyl, chloro-n-propyl, bromo-n-propyl, iodoisopropyl, bromo-n-butyl, bromo-tert-butyl, 1,3,3-trichlorobutyl, 1,3,3-tribromobutyl, chloropentyl, bromopentyl, 2,3-dichloropentyl, 3,3-dibromopentyl, chlorohexyl, bromohexyl, 2,4-dichlorohexyl, 1,3-dibromohexyl, 1,3,4-trichlorohexyl, chloroheptyl, bromoheptyl, fluoroheptyl, 1,3-dichloroheptyl, 1,4,4-trichloroheptyl, 2,4-di-(chloromethyl)heptyl, chlorooctyl, bromooctyl, iodoocetyl, 2,4-di-(chloromethyl)hexyl, 2,4-dichlorooctyl, 2,4,4-tri-(chloromethyl)pentyl, 1,3,5-tribromoocetyl and the halogenated straight and branched chain nonyl, decyl, undecyl and dodecyl.

In the above formula the group

can be, for example: dimethylamino, diethylamino, di-propylamino, dibutylamino, dihexylamino, dioctylamino, didodecylamino, di(tert-butyl)amino, divinylamino, di-allylamino, dibutenylamino, diheptenylamino, didodecenylamino, di(chloromethyl)amino, di(2-chlorobutyl)amino, di(2-fluorobutyl)amino, di(bromomethyl)amino, di(2,2,4-trichlorooctyl)amino, di(2-chloro-2-buten - 1 - yl)amino, di(2 - bromo-2-propen-1-yl)amino, N-methyl-N-butylamino, N-methyl-N-butenylamino, N(chloromethyl)-N-propylamino, diphenylamino, di(2,4-dichlorophenyl)amino, di(2,6-dichlorophenyl)amino, di(2,4,5-trichlorophenyl)amino, di(2,6-dibromophenyl)amino, di(4-iodophenyl)amino, di(2 - fluorophenyl)amino, di(2,3,4,5,6-

2

pentachlorophenyl)amino, di(4-chlorophenyl)amino, and di(2,4,6-tribromophenyl)amino.

The sulfur containing acetamides of the present invention are prepared by a process which comprises reacting a sulfonium salt of the formula

- 10 wherein R, R¹, R², R³, X, X¹, a and b are as defined above with a substantially equimolar amount of an alkaline material in the presence of an inert substantially non-aqueous liquid media. The process is suitably carried out at room temperature, i.e. about 15° C. to about 25° C. However, 15 higher or lower temperatures can be used, the temperature not being critical. Pressure is likewise not a critical factor in the process of this invention. Pressure both above and below atmospheric pressure can be employed although atmospheric pressure is preferred for convenience.

20 Alkaline materials suitable for use in the process of this invention include inorganic bases, for example, alkaline metal hydroxides such as lithium hydroxide, sodium hydroxide, potassium hydroxide, rubidium hydroxide and cesium hydroxide; alkaline earth metal hydroxides such as calcium hydroxide and barium hydroxide; alkali metal hydrides such as sodium hydride, potassium hydride and lithium hydride; metallic oxides such as calcium oxide, magnesium oxide, silver oxide and barium oxide; alkaline metal and alkaline earth metal carbonates such as sodium carbonate, potassium carbonate, magnesium carbonate, calcium carbonate and barium carbonate, and ammonia and ammonia producing compounds such as ammonium hydroxide and ammonium carbonate; and organic bases, 30 for example, aliphatic and aromatic alkoxides such as sodium methoxide, potassium methoxide, lithium methoxide, sodium ethoxide, potassium ethoxide, lithium butoxide, sodium butoxide, sodium phenoxide, lithium phenoxide and potassium phenoxide; primary, secondary and tertiary amines such as methylamine, ethylamine, propylamine, 35 dimethylamine, diethylamine, di-n-propylamine, di-isopropylamine, di-n-butylamine, diisobutylamine, di-sec-butylamine, di-n-amylamine, diisoamylamine, dihexylamine, diheptylamine, dioctylamine, N-methyl-N-ethylamine, 40 N-methyl-N-isopropylamine, trimethylamine, triethylamine, tri-n-propylamine, triisopropylamine, tri-n-butylamine, tri-isobutylamine, tri-sec-butylamine, tri-n-amylamine, triisoamylamine, trihexylamine, triheptylamine and trioctylamine; other amines such as pyridine, 45 morpholine, and mercaptides such as sodium methyl-mercaptopide, sodium ethylmercaptopide, potassium methyl-mercaptopide and potassium phenylmercaptopide.

50

Inert liquid media which can be used in the process of this invention include, for example, alcohols such as methyl alcohol, ethyl alcohol, propyl alcohol, and the like, tetrahydrofuran and ethers such as diglyme, diethyl ether, and the like. An excess of amine reactant also serves as inert liquid media.

The separation of the product from the reaction mixture is readily accomplished. For example the salt, such as an alkali metal halogen salt formed during the reaction, can be separated from the product containing reaction mixture by filtration and the solvent by stripping or distillation, preferably low temperature vacuum distillation. The product can be purified if necessary by any of the conventional means well known in the art, e.g. selective extraction, film distillation, fractional distillation using a carrier gas, elution, fractional distillation under reduced pressure or any suitable combination of these methods.

70 The acetamides of this invention are oily liquid materials which are insoluble in water but somewhat soluble

in many organic solvents, for example alcohols, ketones, hydrocarbons such as benzene, toluene, xylene and the like and chlorohydrocarbons such as chlorobenzene, carbon tetrachloride and the like.

The following examples illustrate the invention. In the following examples as well as in the specification and appended claims, parts and percent are by weight unless otherwise indicated.

EXAMPLE 1

A suitable reaction vessel is charged with about 12 parts of dimethyl(N,N-diethylcarbamoylmethyl)sulfonium chloride and 250 parts of tetrahydrofuran and then 2.3 parts of sodium hydride are added with stirring at room temperature (about 25° C.). After a substantially equimolar amount of hydrogen evolves, the sodium bromide is removed by filtration and the tetrahydrofuran by evaporation under reduced pressure to give about 8.0 parts of N,N-diethyl- α -(dimethylsulfuranylidene)acetamide.

Following substantially the same procedure as in Example 1 above the following sulfur containing acetamides of this invention are prepared—

Example:

- 2 ----- N,N - dimethyl - α - (dimethylsulfuranylidene) acetamide.
- 3 ----- N,N - dibutyl - α - (dimethylsulfuranylidene) acetamide.
- 4 ----- N,N-di-n-butyl - 1 - yl - α - (dimethylsulfuranylidene) acetamide.
- 5 ----- N,N - diphenyl - α - (di-n-butylsulfuranylidene) acetamide.
- 6 ----- N,N-dichloromethyl - α - [di(2,4-dichlorobutyl)sulfuranylidene] acetamide.
- 7 ----- N - methyl - N - phenyl- α -(dimethylsulfuranylidene) acetamide.
- 8 ----- N,N - difluoromethyl - α - (dimethylsulfuranylidene) acetamide.
- 9 ----- N,N - di(2,4 - dichlorophenyl)- α -dimethylsulfuranylidene) acetamide.
- 10 ----- N,N - dimethyl - α - (di-2-chloroethylsulfuranylidene) acetamide.
- 11 ----- N,N - dimethyl - α - (didecylsulfuranylidene) acetamide.
- 12 ----- N,N - didodecyl - α - dimethylsulfuranylidene) acetamide.

The sulfur containing acetamides of this invention are useful per se for various purposes such as fire retardants, rust inhibitors, rust removers, tanning agents, and as chemical intermediates for petroleum additives and agricultural chemicals. For example, the sulfur containing acetamides of this invention are useful in the preparation of nitrones in accordance with the following representative synthesis

wherein R, R¹, R², R³, X, X¹, a and b are as defined above and R⁴ is halogen or lower alkyl, R⁵ is NO₂ or lower alkoxy, n is an integer from 0 to 5 and m is an integer from 0 to 2. The process is usually carried out with substantially equimolar amounts of reactants in the presence of an inert organic medium such as an aromatic hydrocarbon at a temperature from about 0° C. to about 75° C. The above nitrones and more detailed processes for preparing them are disclosed and claimed in applica-

tion Ser. No. 549,153, filed of even date herewith, and now abandoned.

The sulfur containing acetamide salts used as starting materials in the preparation of the compounds of this invention can be prepared by the process disclosed in application Ser. No. 467,750, filed June 28, 1965, now U.S. Pat. No. 3,478,154. Said process comprises reacting a sulfide of the formula

10 wherein R and R¹ are as defined above with a substantially equimolar amount of an α -haloacetamide of the formula

15 wherein R², R³, X, X¹, a and b are as defined above in the presence of an inert liquid medium at a temperature below the decomposition temperature of the sulfide employed.

20 Although the invention is described with respect to specific modifications, the details thereof are not to be construed as limitations except to the extent indicated in the following claims.

25 The embodiments of the invention in which an exclusive property or privilege is claimed are defined as follows:

1. Compound of the formula

30 wherein R and R¹ are each selected from the group consisting of hydrogen, alkyl of not more than 12 carbon atoms and haloalkyl of not more than 12 carbon atoms containing from 1 to 3 halogen atoms, R² and R³ are each selected from the group consisting of alkyl of not more than 12 carbon atoms, alkenyl of not more than 12 carbon atoms and phenyl, X and X¹ are halogen and a and b are each integers from 0 to 5 inclusive.

35 2. Compound of claim 1 wherein R and R¹ are hydrogen.

3. Compound of claim 1 which is N,N-diethyl- α -(dimethylsulfuranylidene)acetamide.

4. Compound of claim 1 which is N,N-dimethyl- α -(dimethylsulfuranylidene)acetamide.

5. Compound of claim 1 which is N,N-diphenyl- α -(di-n-butylsulfuranylidene)acetamide.

40 6. Compound of claim 1 which is N,N-di(2,4-dichlorophenyl)- α -(dimethylsulfuranylidene)acetamide.

7. A compound containing up to 15 carbon atoms of the formula:

55 wherein Z represents N,N-dialkylcarbamyl.
